CLAIM

The ornamental design for a golf scribe, as shown and described.

DESCRIPTION

FIG. 1 is a first perspective view of a golf scribe showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of another state of the golf scribe thereof.

The broken lines shown in the drawings depict portions of the golf scribe in which the design is embodied that form no part of the claimed design.

1 Claim, 9 Drawing Sheets
